UNITED STATES PATENT OFFICE.

JOHN E. HOARE, OF TORONTO, ONTARIO, CANADA.

PLAYER-PIANO.

1,210,474.

Specification of Letters Patent.

Patented Jan. 2, 1917.

Application filed June 1, 1915. Serial No. 31,393.

To all whom it may concern:

Be it known that I, JOHN E. HOARE, a subject of the King of Great Britain, and resident of the city of Toronto, county of 5 York, Province of Ontario, in the Dominion of Canada, have invented certain new and useful Improvements in Player-Pianos, as described in the following specification and illustrated in the accompanying drawings, 10 that form part of the same.

The principal objects of the invention are, to overcome the difficulties met with in the event of any portion of the pneumatics getting out of order, to provide a construction 15 of vacuum action chest which will not be susceptible to the effects of atmospheric conditions and changes of temperature, and further to devise a pneumatic action in which the operating members are individually arranged and may be removed or replaced without interference with the others. 20

A still further object is to improve the valve action so as to obtain the quickest possible response.

25 The principal feature of the invention consists in the novel construction and arrangement of parts, whereby the valves for controlling the operation of the pneumatics are arranged in individual valve chests re- 30 movably connected to the main action chest.

In the drawings, Figure 1 is a plan view of a front side of a portion of the action chest. Fig. 2 is a vertical sectional view taken through the line *a*—*b* Fig. 1 and extending through one of the pneumatics and its controlling valves. Fig. 3 is a perspective view of one of the individual pneumatics. Fig. 4 is a vertical mid-sectional view of a modified form of an individual 40 pneumatic. Fig. 5 is a top plan view of the pneumatic shown in Fig. 4 with the cover removed.

Like numerals of reference indicate corresponding parts in each figure.

45 Referring to the drawings, 1 is the action chest which is formed of a pair of thin metal plates 2 and 3 spaced apart by the longitudinal wood strips 4 forming the longitudinal channels 5. These strips are set in 50 cement and the plates and strips are secured together by machine screws 6 which bind the plates and strips securely in place. This construction of action chest forms an air tight casing which will not be affected by 55 atmospheric or temperature conditions. The chest is provided with an opening 7

connected by suitable ducts to the main bellows chest of the player mechanism through which the air in the action chest is exhausted.

60 8 are individual metal valve chests secured to the inner face of the plate 3 by the screws 9 extending through the action chest, a suitable gasket 10 being interposed between the two metal faces. The valve chests 65 8 are formed with a recess 11 communicating with a hole 12 in the plate 3 leading from one of the channels 5 of the main action chest.

13 is a bellows commonly known as a 70 "pneumatic" having its upper face abutting the under face of the metal valve chest 8 and being rigidly secured thereto by the screws 14 and 15.

The upper block 16 of the pneumatic is 75 formed with a pair of recesses 26 and 21, preferably circular, in the upper face. These recesses are separated from the chamber 11 by a diaphragm 17 of leather or other suitable material which also forms a packing between the upper metal member and the bellows top.

18 is a hole through the upper wall of the valve chest 8 communicating with the outer atmosphere.

85 19 is a duct formed in the walls of the valve chest 8 leading from the hole 18 downwardly at one side of the chamber 11 and communicating with a hole 20 leading to the chamber 21 below the diaphragm 17.

90 22 and 23 are a pair of valves secured to a common spindle 24 which extends through the hole 18, the valve 22 being adapted to rest upon the top of the chest 8 to close the hole 18 and the valve 23 being adapted to close the inner end of said hole. The valve 23 is provided with a buffer 25 on its bottom side adapted to engage the diaphragm 17 extending over the chamber 26.

95 27 is a recess formed in the upper side of the forward end of the member 8 and 28 is a hole in the bottom of the said recess communicating with the valve chamber 11.

100 29 is a hole leading downwardly from the forward end of the recess 27 and communicating with a hole 30 in the upper block 16 of the pneumatic 13.

105 31 is a bracket secured within the valve chamber 11 and supporting a pivotal arm 32.

110 33 is a valve spindle secured to the outer end of the arm 32 and extending through

the hole 28 and having secured to its outer end a disk valve 34.

35 is a buffer secured to the underside of the arm 32 and engaging the portion of the diaphragm extending over the chamber 21.

36 is a plate closing the top of the recess 27 and having a hole 37 therein arranged in alignment with the hole 28. The valve 34 is adapted to normally close the hole 28 and 10 adapted to operate to close the hole 37.

39, 40 and 41 are tubes secured in and extending through the action chest 1 and having their inner ends communicating with holes 42 leading into the recesses 27 under 15 the diaphragm 17. These tubes lead upwardly and pass over the top of the action chest and extend to the tracker bar 43 over which the perforated sheet for operating the device is adapted to pass.

20 44 is a bleed hole leading from the recess 26 and communicating with the valve chamber 11.

25 The lower hinged members 45 of the pneumatics 13 are provided with brackets 46 to which the members 47 for operating the piano action are connected. The members 47 are pivotally supported upon the pivotal arms 48 carried by the brackets 49 which bracket members are provided with 30 outwardly extending flexible fingers 50 carrying the adjustable buffer members 51 to engage the arms 48 as they rise to their upward position.

35 In the operation of this device a partial vacuum is created within the action chest by means of the usual exhaust mechanism and the record traveling over the tracker bar, closes the ends of the tubes 39, 40 and 41 leading to the pneumatics. The valves 22 40 and 34 are held tightly to their seats by the suction closing the holes 20 and 28 and the air is exhausted from the chamber 26 and tubes connecting same with the tracker bar through the bleed holes 44. The air is exhausted from the chamber 21 through the duct 19 and hole 20. As the record sheet travels over the tracker bar and the orifices therein open the tubes leading therefrom the pressure of air passing through the 50 tubes enters the chamber 26 and forces the diaphragm 17 upwardly, thereby lifting the valve 23 to close the bottom end of the hole 20 and simultaneously opening the upper end thereof to the atmosphere. The pressure of air entering the hole 20 flows 55 through the duct 19 and hole 20 to the chamber 21, thereby lifting the valve 34 to close the hole 37 in the plate 36 which is ordinarily open to the atmosphere and coincidentally opening the hole 28. Upon the opening 60 of the hole 28 the air is exhausted from the chamber 26 and from the bellows of the pneumatic 13 through the holes 29 and 30 thereby causing a quick upward movement 65 of the bottom hinged member 45 of the

pneumatic which in turn operates the members 47 to actuate the piano action and cause the striking of the key. Immediately upon the closing of the hole in the tracker bar and the consequent cutting off of the air pressure through the tubes to the diaphragm holding the valve 22 open, the suction within the valve chest closes the primary valve 22 and exhausts the air from the chamber 21, coincidently closing the valve 70 34 and opening the air passage to the pneumatic bellows thereby returning it to its normal position.

75 The action thus described is not new in principle and no claim is made respecting such action, except in so far as the peculiarities of structure in the arrangement of the individual units is concerned.

80 The arrangement of the primary and secondary valves within individual units has numerous advantages, a much quicker response and therefore sensitiveness in action will be had in a structure where primary valves are separated the least possible distance from the secondary valves. Further, 90 the arrangement of two valves within the metallic valve chest obviates the possibility of any leakage between the valves and also the arrangement of two valves within a single unit which can be readily detached from 95 the main action chest without interference with any of the other valve chests renders the matter of repair very simple and also greatly simplifies the matter of original construction.

100 In Figs. 4 and 5 of the drawings, I show a single valve unit constructed in a similar manner to the double valve unit. This element or unit is constructed precisely the same as the outer end of the double unit and 105 has but the one valve 52 supported upon the pivotal arm 53 and operated by the diaphragm 54. This unit may be secured to an action chest similar to that described, the tubes 39, 40 and 41 having communication 110 with a hole 55 communicating with a recess 56 beneath the diaphragm 54.

115 The chamber 57 communicates with the hole 12 in the action chest and a bleed hole 58 is arranged between the chamber 57 and recess 56. This single valve construction is very simple and has all the advantages of ready attachment and detachment claimed for the double valve structure and occupies such small space that it allows of 12 the possibility of a player action being placed in an ordinary piano. The action of the single valve structure is not as responsive as is the double valve structure but has the other advantages mentioned.

120 It will be noted on reference to Fig. 1 that the screws 9 and tubes 39, 40 and 41 are so arranged that the upper, intermediate and lower pairs of pneumatics may be offset the desired distance without complication 125

and the tubes and screws are so arranged as to render the loosening of the screws and the removal of the individual pneumatic units possible without in any way interfering with 5 the tubes connected to the tracker bar.

What I claim as my invention is:—

1. In a piano player, the combination with the piano action, vacuum mechanism, tracker bar and action chest, of individual valve 10 chests removably secured to said action chest and each formed with a vacuum chamber in the underside and a secondary valve chamber in the upper side, a bellows secured to the underside of said valve chest having its 15 interior communicating with the upper chamber of said valve chest, a primary valve arranged in said vacuum chamber, a secondary valve arranged in said secondary valve chamber and extending into said vacuum 20 chamber, an arm pivotally supported within said vacuum chamber and supporting said secondary valve and diaphragms for operating said primary and secondary valves.
2. In a piano player, the combination with 25 the piano action, vacuum mechanism and tracker bar, of an action chest comprising a pair of metal plates spaced apart, a plurality of strips longitudinally arranged and sealed between said plates being spaced 30 apart to form a plurality of vacuum channels connected with the vacuum mechanism, a plurality of individual pneumatics removably secured to the outer face of one of the plates of said action chest each having 35 a vacuum chamber communicating with one of the longitudinal channels in said action chest through holes in the said plate, clamping screws extending through the plates and longitudinal strips of said action

chest and into said pneumatics to hold them 40 in position, openings extending through the plates and strips of said action chest communicating with the diaphragm chambers of the pneumatics, tubes connected with the tracker bar and extending into the holes in 45 the action chest leading to the diaphragm chambers.

3. In a piano player, the combination with the piano action, vacuum mechanism and tracker bar, of an action chest comprising, 50 a pair of metal plates spaced apart, a plurality of wood strips longitudinally arranged between and cemented to said metal plates, said plates and strips being clamped together and forming a plurality of longitudinal vacuum chambers connected to the vacuum mechanism, individual pneumatics having flanged faces abutting the outer face of one of said plates and secured in air tight contact therewith by fastening members extending through said plates and wood strips, 55 said pneumatics having their vacuum chambers communicating with the vacuum chambers in said action chest, a plurality of tubes communicating with the tracker bar and 60 placed in perpendicular arrangement outside of the action chest on the side opposite from the pneumatics and having their terminal ends extending through holes in said plates and strips and communicating with 65 the valve operating mechanism in said pneumatics, the pneumatic fastening means being arranged between said perpendicularly arranged tubes.

Signed at the city of Toronto, Canada, 75 this 13th day of May 1915.

JOHN E. HOARE.
